N. O. COCHRAN

T-SQUARE

Filed Feb. 16, 1927

Inventor
Noble O. Cochran

By Clarence O'Brien
Attorney

UNITED STATES PATENT OFFICE.

NOBLE O. COCHRAN, OF MORRISVILLE, PENNSYLVANIA.

T SQUARE.

Application filed February 16, 1927. Serial No. 168,632.

My present invention pertains to **T** squares such as used in conjunction with drawing boards and angles; and it contemplates the provision of a **T** square so characterized that greater speed may be attained in the inking of a drawing when the **T** square is employed.

To the attainment of the foregoing, the invention consists in the improvement as 10 hereinafter described and definitely claimed.

In the drawing forming part of this specification:—

The figure is a perspective showing the **T** square constituting the preferred embodiment of my invention as properly arranged relative to a drawing board, and also to an angle.

In the drawing 1 is a drawing board, 2 is a conventional angle, and 3 is the **T** square 20 of my invention.

My novel **T** square comprises a head 4 and a stem 5 fixed with respect to the head 4 and extending at right angles thereto. The head 4 in accordance with my invention is 25 rabbeted in the direction of its length at its inner edge and corner remote from the stem 5, as designated by 6, and the stem 5 in accordance with my invention is rabbeted along one of its longitudinal edges and at 30 one of its corners remote from the head 4, as designated by 7.

The rabbet 6 in the head 4 is designed to receive one corner of an edge of the board 1, after the manner shown in the drawing, and the rabbet 7 in the stem 5 is adapted to receive and support one end of an angle 35 after the manner illustrated.

The angle 2 is designed to be used in conjunction with the stem 5 of the **T** square in the manner indicated in cases where the horizontal lines of a drawing are inked first, the angle 2 being placed in the rabbet 7 for the inking of the vertical lines of the drawing. In this connection it will be understood that when relatively arranged as 45 stated, the angle 2 will be separated by an intervening space from the paper or in other words clearance will be afforded between the surface of the paper and the angle 2, and consequently notwithstanding the horizontal 50 lines may be wet the vertical lines may be inked without affecting the horizontal lines. From this it follows that no delay need be entailed in inking the vertical lines 55 after inking of the horizontal lines.

I would also have it understood that cases where the vertical lines are inked first, the head 4 of the **T** square is arranged that its rabbet 6 receives one corner of the board 1, this arrangement affording a space or clearance between the under side of the stem 5 and the surface of the paper on the board 1 so that horizontal lines may be inked even though the vertical lines may still be wet.

I would further have it understood that by virtue of my novel **T** square characterized as described, either vertical or horizontal lines may be inked, notwithstanding nearby lines may not be dry.

It will be apparent from the foregoing 70 that while my novel **T**-square is practically advantageous for the reasons stated, the said **T**-square is not materially increased in cost. On the other hand, the production of my novel **T**-square costs but little if any more 75 than an ordinary **T**-square of corresponding material.

It will also be apparent from the foregoing that notwithstanding the novel characteristics of my improved **T**-square is susceptible of being used to advantage in the same manner as an ordinary **T**-square.

I have explicitly described the preferred embodiment of my invention in order to impart an exact understanding of the said 85 embodiment in all of its details. I do not desire, however, to be understood as limiting myself to the precise construction illustrated, my invention being defined by my appended claim within the scope of which 90 modifications may be made without departure from my invention. For instance when desired the stem 5 may be rabbeted along both of its longitudinal edges, the additional rabbet being identical with the one illustrated. 95

Having thus described the invention, what I claim is:—

As a new article of manufacture, a **T**-square having a head and a stem extending at an angle to the head; the head having the 100 lower corner of its edge for use in opposed relation to a drawing board, rabbeted to seat one corner of an edge of the board, and the stem having one of its upper longitudinal edges similarly rabbeted.

In testimony whereof I affix my signature.

NOBLE O. COCHRAN.
